UNITED STATES PATENT OFFICE.

ROSCOE C. PATTISON, OF ROCHESTER, NEW YORK, ASSIGNOR OF ONE-HALF TO WILLIAM A. EVERITT, OF ROCHESTER, NEW YORK.

APPARATUS FOR USE IN MAKING CORES OR THE LIKE.

1,305,667.

Specification of Letters Patent. Patented June 3, 1919.

Application filed May 6, 1918. Serial No. 232,685.

To all whom it may concern:

Be it known that I, Roscoe C. PATTISON, citizen of the United States, residing at Rochester, in the county of Monroe and 5 State of New York, have invented a new and useful Improvement in Apparatus for Use in Making Cores or the like, of which the following is a specification.

This invention relates to apparatus for 10 use in the forming of molds and sand cores of the kind used in metal molding.

One of the objects of the invention is to 15 provide an apparatus of this kind by means of which unskilled persons can make cores or molds which would otherwise require the services of experienced core makers or molders.

Other objects of the invention are to provide an apparatus of this kind by means of 20 which cores and molds can be made more rapidly and with greater ease; also to provide an apparatus of this kind with means for enabling a core box or other sand container to be quickly and accurately positioned on the supports therefor; also to provide apparatus of this kind of improved construction for drawing the core box or pattern from the sand; also to so construct apparatus of this kind as to enable it to be 25 placed into operative relation to a jolter so that a sand container can be moved with the minimum loss of time from the jolter to the means for drawing the core box or pattern from the core or mold; also to provide apparatus of this kind with pivoted arms for 30 supporting a sand container, which may be swung into and out of operative positions; also to provide supporting members or tables which are so made as to adjust themselves to sand containers of irregular shapes; also to 35 provide the apparatus with means for quickly attaching a sand forming device to or detaching it from the apparatus; also to improve apparatus of this kind in other respects hereinafter specified.

In the accompanying drawings:

Figure 1 is a front elevation, partly broken away, of an apparatus, embodying the invention, for use in making cores or 40 molds.

Fig. 2 is a sectional plan view thereof on

line 2—2, Fig. 4, showing the lower portion of the apparatus.

Fig. 3 is a central sectional elevation of the lower portion of the apparatus on line 55 3—3, Fig. 2.

Fig. 4 is a side elevation thereof partly in section.

Fig. 5 is a perspective view of a holding arm and a socket therefor which is attached 60 to a core box, pattern, or other sand forming device.

The apparatus will be hereinafter described as applied to making cores but it is not intended thereby to limit the apparatus 65 to such use since it will be understood that the apparatus can also be used for making molds.

The apparatus is provided with a base A 70 which rests on a floor or other suitable support *a*. The base is preferably arranged in operative relation to a jolter having a base portion B and a vertically movable table or platform *b* on which the core boxes or other sand forming devices are placed for the purpose of shaking or jolting the sand to pack 75 the same in the containers. The jolter may be of any suitable or desired construction and of itself forms no part of this invention. The apparatus includes an upright frame 80 member or column C which is preferably of hollow cylindrical form and is suitably secured on the base in any desired manner. In the construction shown, the column is provided at its lower end with a collar *c* 85 which may be secured to the base A by means of bolts *c*' or the like.

The apparatus is provided with suitable means for supporting a core box or other forming member D either in its upright position in which the box can be filled with sand, or in its inverted position in which the box can be withdrawn from the core. The core box supporting means are preferably constructed so as to be moved into and out 90 of an operative position over the jolter platform *b*. In the construction shown for this purpose, two core-box supporting arms E are provided which are suitably pivoted on the frame A so as to swing 95 in a substantially horizontal plane into their operative positions over the jolter,

or to swing in opposite directions to the sides of the jolter. The arms E are pivoted to swing about a bolt or pivot member e suitably secured on a part of the base A, the pivot member being arranged, in the construction shown, at the base of the column C. The arms have straight portions e' adjacent to their inner pivoted ends, and offset portions e² at their outer ends, on which the 10 supports for the core boxes are mounted. The straight portions e' of the arms are preferably supported intermediate of their ends on an arc-shaped upwardly extending projection or track e³ formed on the base A. 15 The supporting arms may be of any other suitable construction or, if desired, only one supporting arm may be used.

The means on the ends of the arms E for supporting the cores or core boxes may be 20 of any suitable kind but are preferably made so as to adapt themselves to core boxes of irregular shapes. The means shown in the construction illustrated include core supports or landings F which are pivoted at f on posts or parts f' secured on the arms E. Each of the posts is preferably provided with a lower threaded portion extending through a slot f² formed in the end of the arm E and is held in the desired position by 25 any suitable means, such for example as nuts f³ f⁴ by means of which the post can be adjusted vertically as may be desired, or lengthwise of the slot f². In the construction shown, the upper end f⁵ of each post is 30 substantially rectangular in cross-section and extends into a slot f⁶ in the core support or landing F. By means of this construction the core box supports or landings may assume inclined positions as shown in Fig. 35 3, or horizontal positions as shown in the other figures, so that the apparatus is adapted to operate in connection with core boxes of irregular shapes, for example with core boxes having inclined top portions, as shown 40 in Fig. 3. In order to hold the core supports or landings in the desired positions, suitable means are provided for resisting the movement of the core supports about their pivots. For this purpose, in the construction shown, 45 a spring G is provided for each support, the ends of the springs being adapted to engage serrated portions g of the supports for holding the same in adjusted positions and for resisting the movement of the supports relatively to the spring. In this manner the core box supports will be yieldingly held in any position which they assume when the core box is placed thereon. The springs may be held in operative relation to the core box 50 supports in any suitable manner, being provided in the construction shown with rectangular slotted portions g' through which the upper portion f⁵ of the post f' extends.

The means for drawing the core boxes 55 from the cores are mounted on the column

or upright frame members C and are preferably constructed as follows:

The upper portion of the column C is provided with a forwardly extending part or projection H having at its front end upright 70 guide bearings h h' in which a sliding rod or member h² of the core box drawing device is arranged. The slide rod h² is held against turning by any suitable means, the rod shown in the drawings being made square or 75 rectangular in cross-section and the guide bearings h h' being also square or rectangular. The slide rod h² is provided at its lower end with suitable holding means for the core boxes, a holder I being provided in the construction shown, which is suitably secured to the bottom of the sliding member h² and which is preferably provided with a roller or sheave I' which is adapted to bear against the upright column C to prevent the slide 80 rod h² from binding in the bearings.

The core box holder I is provided with suitable means for mounting the core box on the holder, in such a manner that the core box may either be held in upright position 90 in which the sand may be packed in the box, or in inverted position to permit the core box to be withdrawn from the core. The holding means for the core box are also preferably so constructed that the core box 95 can be inverted while the same is supported on the holder and with means for holding the core box in proper alignment with the slide rod h² so that the core box can be accurately withdrawn from the core. In the construction shown for this purpose, the core box holder is provided with a socket or hole adapted to receive a holding arm K which may be suitably attached to the core box. The holding arm is provided at its inner 100 end with a portion k of substantially circular cross-section which is adapted to enter into a portion k' of the socket of similar cross-section, thus enabling the core box to be swung about the axis of the arm K to 110 place the core box either into an inverted or an upright position. The means for holding the arm K in either upright or inverted positions may be of any suitable construction, the holding arm shown being provided 115 for this purpose with an intermediate portion k' of substantially square or rectangular cross-section and adapted to engage with a portion of similar cross-section at the outer end of the core box holder I. By means of 120 this construction the core box may be readily swung about the axis of the holding arm K by withdrawing the holding arm from the socket I until the square or rectangular portion of the arm is out of engagement with 125 the corresponding part of the socket. When the core box is in the correct upright or inverted position, the core box is pushed toward the back of the apparatus so that the intermediate portion k' of the arm engages 130

in the socket, which will hold the core box against movement. K' represents a set screw arranged in the core box holder and adapted to engage the arm K to hold the 5 same in the socket in case it is not desired to use the apparatus for inverting the core box. Any other means may be provided for holding the arm K so that the core box can be accurately held either in upright or inverted position.

The outer end of the holding arm may be connected with the core box in any suitable manner. In the construction shown in the drawings, the holding arm is detachably 15 connected with the core box, being for this purpose provided with a wedge-shaped portion k^2 adapted to engage in a similar portion of a socket member k^3 which is suitably secured on the core box. The socket member k^3 is so secured to the core box that when 20 the holding arm K is in engagement with the socket member the sides of the core box will be alined with the slide rod h^2 , so that the core box can be accurately drawn from 25 the core.

The weight of the core box and the core box holder is preferably counterbalanced so that very little effort is required to draw the core box from the core. For this purpose a 30 weight L is provided which is preferably arranged within the column C . This weight is connected by a cable or belt l to the core box holder I , the belt passing over the pulleys or sheaves l' l^2 which are pivoted in 35 the projection H of the column. Any other means for counterbalancing the weight of the core box and core box holder may be employed.

M represents a vibrator of any suitable 40 kind which is preferably mounted on the core box holder I and which may be actuated by the operator in drawing the box from the core so as to loosen the box from the core, the vibrations being transmitted 45 from the core box holder I through the holding arm K to the core box. This vibrator may be of any well known or desired construction and of itself constitutes no part of this invention.

50 By means of the apparatus described the core box is filled with sand and placed on the jolter platform b . The jolter packs the sand in the core box D , which may then be raised and placed on the holding arm K by 55 inserting the wedge-shaped portion k^2 thereof into the socket k^3 of the core box. The supporting arms E are then swung inwardly over the jolter into a position to receive the core box. A cover d is placed on the core 60 box and the arm K is drawn out so as to disengage the intermediate portion k' thereof from the socket of the core box. The core box is then inverted and lowered on the supports or landings F , which adjust 65 themselves in accordance with the shape of

the core box and are retained in their adjusted positions by the springs G . The vibrator M is then actuated and the core box is drawn upwardly away from the core. No skill is required in withdrawing the core 70 box from the core since it is only necessary to move the core box upwardly, the slide rod h^2 serving to properly guide the core box in its movement relatively to the core.

The apparatus for drawing the core boxes 75 from the cores need not be used in connection with the jolter, and if desired the apparatus can be used only for drawing core boxes from the cores, in which case the arms E remain at all times in the positions shown 80 in full lines in Fig. 2.

Since no particular skill is required to make cores or molds by using the apparatus described, the services of high priced core makers can be dispensed with and the cores 85 or molds can also be made much more rapidly since the careful and precise work heretofore necessary for drawing the core boxes or patterns is eliminated. The counterbalanced holder also facilitates the drawing of 90 the forming device from the sand. By providing the apparatus with movable supports, such as the arms E , the distance through which the core box must be moved to perform the various operations on the core is 95 reduced to a minimum.

I claim as my invention:

1. In an apparatus for use in making cores or the like, the combination with a core box, of a drawing member movable substantially 100 in a straight line and connected with said core box to draw the same from a core, and a member for supporting the core and which is movable into and out of operative relation to said drawing member.

2. In an apparatus for use in forming sand or the like, the combination with a sand forming device, of a drawing member movable substantially in a straight line and connected with said sand forming device to draw the same from the sand, and a supporting member which is movable into a position to receive the sand and into a position out of the path of movement of said forming device supported on said drawing 110 member.

3. In an apparatus for use in forming sand or the like, the combination with a forming device, of a drawing member secured to said forming device, and a supporting member which is pivoted to swing into operative relation to said drawing member, and to swing to one side of the path of movement of said drawing member, one of 120 said members being movable relatively to the other member to cause the forming device to be withdrawn from the core.

4. In an apparatus for use in forming sand or the like, the combination with a sand forming device, of a drawing member mov- 130

- able substantially in a straight line and secured to said forming device, said drawing member guiding said forming device while the same is being drawn from the sand, and 5 a pair of supporting arms adapted to swing into positions to receive the formed sand from said drawing member and into positions out of operative relation to said drawing member.
- 10 5. In an apparatus for use in making cores or the like, the combination with a core box, of a holder secured to said core box, a part on said holder adapted to be turned to permit the core box to be inverted, and means 15 for moving said holder with said core box when inverted in a substantially straight line to draw the core box from the core.
6. In an apparatus for use in making cores or the like, the combination with a core box, 20 of a drawing member, a member on said drawing member which is secured to said core box and which is adapted to be turned to enable the core box to be inverted and means for raising said drawing member and 25 the core box when inverted for drawing said box from the core.
7. In an apparatus for use in making cores or the like, the combination with a core box, of a drawing member movable substantially 30 in a straight line and secured to said core box to guide said core box when the same is being withdrawn from a core, and a holding arm for said core box pivotally mounted on said drawing member and by 35 means of which said core box may be inverted whereby the drawing member when being raised draws the core box from the core.
8. In an apparatus for use in making cores 40 or the like, the combination of a drawing member movable substantially in a straight line and adapted to draw a core box from a core, a holding arm for said core box pivotally mounted on said drawing member and 45 by means of which said core box may be inverted, and guide means for securing said holding arm in positions to hold said core box positively either in an upright or an inverted position.
- 50 9. In an apparatus for use in making cores or the like, the combination of a drawing member movable substantially in a straight line and adapted to draw a core box from a core, a holding arm having a substantially 55 cylindrical portion journaled in a corresponding bearing in said drawing member, and guide parts on said holding arm adapted to engage said drawing member to hold a core box positively in upright and inverted 60 positions.
10. In an apparatus for use in making cores or the like, the combination of a drawing member movable substantially in a straight line, a core box supporting arm which is pivotally 65 mounted on said drawing member, and a rectangular portion on said arm adapted to enter into a correspondingly shaped hole in said drawing member for holding said core box in either an upright or an inverted position. 70
11. In an apparatus for making cores or the like, the combination of a core box supporting arm which is movable substantially in a straight line, means for permitting said arm to be swung to place said core box into 75 an upright or an inverted position, and means for attaching a core box to said arm so that the core box is supported from said arm when inverted, said arm when being raised drawing said core box from said core. 80
12. In an apparatus for making cores or the like, the combination of a core box supporting arm which is movable substantially in a straight line, means for permitting said arm to be swung to place said core box into 85 an upright or an inverted position, and a member on said core box adapted to receive a part of said arm for securing the core box to said arm.
13. In an apparatus for forming sand or 90 the like, the combination with a sand forming device, of a supporting arm for said device which is movable substantially in a straight line, said arm having a substantially wedge-shaped end portion, and a securing 95 device on said forming device to which said wedge-shaped portion of the arm can be secured.
14. In an apparatus for use in making cores or the like, the combination of a drawing member, a holding arm arranged on said drawing member and adapted to support a core box, said holding arm having a substantially cylindrical portion engaging a corresponding portion in said drawing member, 100 and a substantially rectangular portion adapted to engage a corresponding portion of said drawing member to hold said core box either in an upright or an inverted position. 105
15. In an apparatus for use in forming sand, the combination with a sand forming device, of a frame having an upright portion, a drawing member movable substantially in a straight line and adapted to draw 110 said forming device from the sand, a guide bearing on said frame for said drawing member, means for supporting said forming device on said drawing member at one side of said bearing, and a roller on said drawing member at the opposite side of said bearing and engaging the upright portion of said frame to prevent said drawing member from binding in said guide means. 115
16. In an apparatus for use in forming sand, the combination with a sand forming device, of a frame having a hollow upright portion, a drawing member movable sub- 120
- 125

stantially in a straight line and adapted to draw said forming device from the sand, a guide bearing on said frame for said drawing member, means for supporting said forming device on said drawing member at one side of said bearing, a counterbalance weight on said hollow frame portion, and means on said drawing member at the opposite side of said bearing and engaging said hollow frame portion for supporting said drawing member to keep the same from binding in said bearing.

17. In an apparatus for use in forming sand or the like, the combination with a sand forming device, of a drawing member movable substantially in a straight line and adapted to draw said forming device from the sand, and vibrating means mounted on said drawing member, the vibrations being transmitted from said drawing member to said forming device.

18. In an apparatus for use in forming sand or the like, the combination with a sand forming device, of a drawing member movable substantially in a straight line and adapted to draw said forming device from the sand, an arm mounted on said drawing member and connected with said forming device, said arm being movable to support said forming device in different positions, and a vibrator mounted on said drawing member.

19. In an apparatus for use in forming sand or the like, the combination with a sand forming device, of a drawing member movable substantially in a straight line and adapted to draw said forming device from the sand, a jolter arranged below said drawing member, and a member for supporting the formed sand which is movable into and out of a position above said jolter to receive the sand from said drawing member.

20. In an apparatus for use in forming sand or the like, the combination with a sand forming device, of a drawing member movable substantially in a straight line and adapted to draw said forming device from the sand, a jolter arranged below said drawing member, and a pair of swinging arms mounted on said frame and adapted to be moved into a position above said jolter to receive the formed sand from said drawing member.

21. In an apparatus for use in forming sand, the combination with a frame, a drawing member movable substantially in a straight line and guided on said frame, a supporting arm pivoted at its inner end on said frame and having an outer end adapted to swing into and out of a position underneath said drawing member, and a projection on said frame for supporting said arm intermediate of the ends thereof.

22. In an apparatus for use in forming

sand, the combination with a forming device, of a frame, a drawing member for drawing said forming device from the sand, a jolter arranged in proximity to said frame, and arms pivoted on said frame and movable into and out of position to receive the formed sand.

23. In an apparatus for use in forming sand, the combination of a sand forming device, of a drawing member adapted to draw said forming device from the sand, arms adapted to swing into a position under said drawing member to receive the sand, and supports for the formed sand mounted on said arms and adapted to be moved by the forming device into different inclined positions.

24. In an apparatus for use in forming sand, the combination of a sand forming device, of a drawing member adapted to draw said forming device from the sand, a member for supporting the sand which is movable into and out of operative relation to said drawing member, and a support pivotally mounted on said supporting member and adapted to swing into a position to conform to the shape of the sand forming device.

25. In an apparatus for use in forming sand, the combination of a sand forming device, of a drawing member adapted to draw said forming device from the sand, a member for supporting the sand which is movable into and out of operative relation to said drawing member, a support pivotally mounted on said supporting member, and means for yieldingly holding said support in any position in which the same is placed when receiving the sand.

26. In an apparatus for use in forming sand, the combination of a sand forming device, of a drawing member adapted to draw said forming device from the sand, a member for supporting the sand which is movable into and out of operative relation to said drawing member, a support pivotally mounted on said supporting member, means for yieldingly holding said support in any position which the same is placed when receiving the sand, and means for adjusting said support relatively to said supporting member.

27. In an apparatus for use in forming sand, the combination with a sand forming device, of a drawing member adapted to draw said device from the sand, a pair of arms pivoted on said apparatus and adapted to swing into a position below said drawing member, and supports pivotally mounted on said arms to swing into positions to conform with the forming device.

28. In an apparatus for use in forming sand, the combination with a sand forming device, of a drawing member adapted to

draw said device from the sand, an arm pivotally mounted on said apparatus and adapted to swing into a position below said drawing member, a support pivotally mounted on said arm and adapted to swing into any position to conform with the shape of the sand forming device, and a spring for yieldingly holding said support in a position

into which the same is moved by said forming device.

Witness my hand, this 30th day of April, 1918.

ROSCOE C. PATTISON.
